PUMPING APPARATUS

Leo A. Shortt, Waukon, Iowa

Application September 10, 1931
Serial No. 562,032

1 Claim. (Cl. 185—37)

This invention is a pumping apparatus or mechanism whereby the energy stored in wound springs may be utilized for driving or operating a water pump or like device.

5 One object is to provide a practical and substantial form of such mechanism which may be compactly associated with the pump and having two spaced spring drums for positioning one at each side of the pump, with gear and lever connections directly to the pump rod.

Another object is to provide a pumping apparatus including dual spring and gear assemblies wherein energy may be stored by crank action and redelivered as desired for the operation of the 10 pump.

With these and such other objects and advantages in view as may be developed in the following specification, a preferred embodiment of the invention is described in the said specification 20 and illustrated in the accompanying drawing wherein

Figure 1 is a side elevation of the present embodiment of the invention as applied to a conventional form of pump;

25 Figure 2 is a rear elevation;

Figure 3 is a section through one of the spring drums showing the coil spring mounted inside and the drive gear outside.

In carrying out the invention, suitable uprights 30 1 are anchored at 2 at either side of the pump 3 and slightly to the rear thereof as shown. A crank shaft 4 is journaled transversely through the upper ends of these supports and a crank 5 is fixedly mounted at one end thereof. Heavy 35 drive gears 6 are loosely mounted upon the shaft 4 and disposed immediately at either side of the pump casing 7 as shown in Figure 2. Spring drums 8 are anchored to these gears, the shaft 4 being journaled through the outer sides of the 40 drums inside the supports 1. Suitably long and strong band springs or clock springs 9 are mounted within the drums 8, their inner ends being secured to the shaft 4 as shown at 10 and their outer ends to the drum casings as shown at 11.

45 Ratchets 12 are anchored upon the outer ends of the shaft 4 and pawls 13 are pivoted at 14 to the supports 1 and placed in engagement with the ratchets. A screw brake 15 has its threaded stem passed through a lug 16 extended from one of 50 the supports, the said lug being provided with an interiorly threaded bore 17 for that purpose. The outer end of the brake is provided with a hand wheel 18 and the inner end with a foot 19 adapted to bear upon the surface of the drum 8 at that 55 side. Pinion gears 20 are journaled upon stub

shafts 21 anchored at 22 upon each side of the pump casing, and are placed in mesh with the drive gears 6. Drive wheels 23 are rigidly mounted upon the outer sides of the pinions 20 and have laterally aligned and eccentrically positioned 60 crank pins 24 extended therefrom. A U-shaped connecting link 25 has its free ends journaled at 26 upon the pins 24, while the bight of the link is journaled at 27 to the upper end of the vertically reciprocating pump rod 28. The arrangement is such that a line connecting the centers of the pinions 20 will pass through the pump rod 28, whereby the pins 24 swing equally to either side of the rod 28 in the operation of the device. 65

In use the springs 9 are wound up by turning 70 the crank 5, the brake 15 being first set to prevent the rotation of the drums 8. When the springs are fully wound, their energy may be released as desired for the operation of the pump rod, by merely unscrewing the said brake. This 75 assembly presents a very compact and powerful spring actuated mechanism for the purpose described.

While I have herein described a certain specific 80 manner and method of constructing and assembling the elements of my invention, it is understood that I may vary from the same in minor details, not departing from the spirit of my invention, so as best to construct a practical device for the purpose intended, as defined in the 85 appended claim.

I claim:

In a device of the kind described, spaced uprights, a crank shaft journaled through the uprights, spring actuated driving gears mounted at 90 either end of the crank shaft inside of the uprights, pinion gears mounted above and in mesh with the driving gears and at one side of a plane passed vertically through the crank shaft, drive wheels at the outer sides of the pinions, laterally 95 aligned crank pins on the drive wheels, and a U-shaped link connecting the said crank pins of the drive wheels.

LEO A. SHORTT.
